UNITED STATES PATENT OFFICE.

GEORGE HARRISON AND ERNEST GASKELL STERNDALE BENNETT, OF MOOSE JAW,
SASKATCHEWAN, CANADA.

RETORT.

1,363,588.

Specification of Letters Patent. Patented Dec. 28, 1920.

Application filed March 27, 1919. Serial No. 285,699.

To all whom it may concern:

Be it known that we, GEORGE HARRISON and ERNEST GASKELL STERNDALE BENNETT, subjects of the King of Great Britain, and 5 both residents of the city of Moose Jaw, in the Province of Saskatchewan, Dominion of Canada, have invented certain new and useful Improvements in Retorts, of which the following is a specification.

10 This invention relates to improvements in retorts, particularly adapted for use in the recovery of gas from straw, and the objects of the invention are to accelerate the generation of the gas from the straw, to facilitate 15 consuming the flue gases or products of combustion emitted from the fire chamber or furnace, and converting the same into heat, so intensifying the heat of the retort and providing for the quick and abundant generation of gas.

Further objects are to uniformly heat the retort, so that the contents will be charred uniformly and thus a maximum yield of gas will be obtained, to render the several parts 25 easily accessible for inspection and repair, and generally to adapt the retort to better perform the functions required of it.

With the above and other objects in view the invention consists essentially of the improved construction hereinafter described and set forth in the following specification and accompanying drawings forming part 30 of the same.

In the drawings:

35 Figure 1 is a longitudinal section of the improved retort.

Fig. 2 is a plan view, the casing being in section.

40 Fig. 3 is a front elevation of the improved retort.

Fig. 4 is a vertical section through the retort.

45 Fig. 5 is a front elevation of the intensifier located toward the rear of the central conduit of the retort.

Fig. 6 is a front elevation of the intensifier located intermediate of the length of the retort.

50 Fig. 7 is a front elevation of the intensifier located in front of the intensifier shown in Fig. 6.

Fig. 8 is a front elevation of the intensi-

fier located in front of the intensifier shown in Fig. 7.

Like characters of reference refer to like 55 parts in the several figures.

Referring to the drawings, A represents the improved retort which is operatively supported in a casing 10, the retort being spaced from the walls of the casing to form 60 smoke passageways.

Below the retort a grate 11 is located and extends rearwardly of the casing for part of the length thereof, and is supported by the front wall of the casing and the wall 12. 65

A wall 13 extends rearwardly in the casing and is angularly disposed to the wall 12, and at the rear end of the wall 13 an intensifier 14 is located.

This intensifier extends transversely across 70 the lower end of the casing 10, as is illustrated in Fig. 4, and consists of a trough comprising front and rear walls, and a bottom wall, the front and rear walls being provided with a plurality of perforations 15, 75 while the trough is filled with a non-combustible and heat retaining material such as asbestos.

A gas supply pipe 16 is located in the lower end of the trough, and provides means 80 whereby the asbestos is heated to the desired temperature, for an object which will be made clear hereafter.

The retort A is cylindrical and horizontally disposed and provided with a central 85 passageway 17 which is open from one end of the retort to the other, the rear end of the conduit communicating with the smoke passageway at the rear of the casing, the front communicating with a smoke box 18 90 which is formed on the front of the casing 10.

It will be seen that the retort forms an annular chamber 19 which is closed at the rear end, while the front end is provided 95 with openings or doorways 20, the walls of which are splayed, and these openings are closed by a plurality of doors 21 of the man-hole type, the doors being secured in position by clamps 22.

100 A gas outlet pipe 23 extends longitudinally through the upper portion of the retort A, and is formed with a plurality of orifices therein, the perforated portion of

the pipe being substantially the whole length of the retort, so that the gases generated during the operation of destructive distillation of the straw are readily delivered to the 5 pipe 23 and carried to a gasometer.

In the conduit 17 a plurality of intensifiers 24, 25, 26 and 27 are provided, each consisting of a pair of spaced walls having perforations 28, 29, 30 and 31 therein and 10 these perforations decrease in size but increase in number from the rearmost intensifier to that located adjacent to the front end of the conduit 17, such reduction in the area of the orifices being illustrated in Figs. 15 5 to 8.

The plates forming the front and rear walls of these intensifiers are designed to house a non-combustible and heat retaining substance such as asbestos, which is heated 20 to the desired temperature by a plurality of gas jets 32 extending into each intensifier and connected to a supply pipe 28.

It is advisable that the smoke or products of combustion should be made to pass back- 25 wardly and forwardly, *i.e.*, below, through and over the top of the retort A, so that they will deliver up to the retort a maximum of heat units, and it is also advisable that in this passage of the products of combustion an after burning to complete the combustion of the flue gases should take place, and it is for this purpose that the intensifiers are provided.

To control the passage of the flue gases a 35 baffle plate 34 is provided at the rear end of the casing and is located just above the conduit 17, the said plate extending transversely across the casing 10 and being provided with a pair of longitudinally extending arms or portions 35 which are illustrated in Fig. 2, and which extend longitudinally of the casing, engaging with the inner wall of the casing and with the upper portion of the cylindrical wall of the 45 retort.

In this manner it will be seen the products of combustion are caused by the draft of the furnace to flow from the fire box through the perforation 15 in the intensifier 24, upwardly behind the retort 10, and thus through the central conduit 17, and through the several intensifiers 24, 25, 26 and 27, after which the products of combustion enter the box 18 and are then delivered to the 55 upper portion of the casing above the baffle wall 34 and arms 35.

The products of combustion, after passing along the top of the retort are delivered to the smoke stack 26.

When the retort is in use the doors 21 are opened and the straw packed into the annular body 19 of the retort A, whereupon the doors are closed and secured in position by the clamps 22.

The fuel on the fire bars 11 is then ignited

and the intensifiers 24, 25, 26 and 27 are heated by means of gas delivered through the pipes 16 and 33 to the intensifiers, so that the asbestos is brought to a state of incandescence. The gas supplied to the 70 burner may be in proportion to that driven off by the destructive distillation. It will be found that there is sufficient air through the retort to maintain combustion.

As the products of combustion pass 75 through the intensifier 14 a partial after burning of the flue gases takes place, so developing a greater heat around the retort and through the conduit 17 the completion of the after burning of the flue 80 gases takes place as the said flue gases pass through the intensifiers 24, 25, 26 and 27 in the passageway 17.

The object in having the orifices through the intensifier in the central conduit 17 85 gradually reducing in size is to split the flue gases up into a number of streams, so that the flue gases are intimately brought into contact with the incandescent asbestos of the intensifiers, so that a complete combustion of the flue gases will take place.

It will thus be seen that by this arrangement a uniform heat will be distributed to the exterior of the retort A and the wall of the conduit 17, so that the distributive 95 distillation of the straw in the retort will be uniform and the gas will be quickly evolved and delivered to the pipe 23.

From this description it will be seen that we have invented a retort which can be advantageously utilized for the production of 100 gas from straw and other vegetable matter, and wherein a complete combustion of the heating fuel is obtained, so that the distillation of the straw in the retort is carried out with the result that a maximum yield of gas is obtained.

As many changes could be made in the above construction, and many apparently widely different embodiments of my invention, within the scope of the claims, constructed without departing from the spirit or scope thereof, it is intended that all matter contained in the accompanying specification and drawings, shall be interpreted as illustrative and not in a limiting sense.

What we claim as our invention is:

1. A retort for the production of gas from straw, comprising a cylindrical body 120 portion having a conduit therethrough, and an intensifier in the conduit comprising a pair of spaced perforated walls having a non-combustible and heat retaining filling therein.

2. A retort for the production of gas from straw, comprising a cylindrical body portion having a conduit therethrough, a plurality of intensifiers in the conduit, each comprising perforated walls having a non- 130

combustible and heat retaining filling therein, the perforations decreasing in area from the rearmost intensifier toward the foremost intensifier.

- 5 3. A retort for the production of gas from straw, comprising an annular chamber for the straw, a conduit extending longitudinally therethrough, a grate below the chamber, a trough at the rear of the grate 10 having a filling of heat retaining material, a casing inclosing the chamber and forming smoke passageways, a wall located at the rear of the chamber and along the sides thereof, the products of combustion being 15 so controlled that they flow rearwardly and forwardly, and then rearwardly to the retort to uniformly heat the same.

4. A gas retort comprising an annular chamber for straw, a conduit therethrough, a plurality of perforated plates extending 20 transversely across the conduit and arranged in pairs in spaced relation with a filling of heat retaining material for each pair of plates, a gas supply pipe having a plurality of jets each located between a pair of spaced 25 plates, and a perforated gas offtake pipe extending into the retort.

In witness whereof we have hereunto set our hands in the presence of two witnesses.

GEORGE HARRISON.

ERNEST GASKELL STERNDALE BENNETT.
